(57) CLAIM

The ornamental design for a baby seat, as shown and described.

DESCRIPTION

FIG. 1 is a front perspective view at first position of a baby seat showing a new design;

FIG. 2 is a side view at first position of the baby seat showing the new design; the other side being a mirror image;

FIG. 3 is a front view at first position of the baby seat showing the new design;

FIG. 4 is a rear view at first position of the baby seat showing the new design;

FIG. 5 is a bottom view at first position of the baby seat showing the new design;

FIG. 6 is a front perspective view at second position of the baby seat showing the new design; and,

FIG. 7 is a top view at second position of the baby seat showing the new design.

The areas of the drawings shown in light gray tone and outlined in dotted lines are for illustrative purposes only and form no part of the claimed design.
